UNITED STATES PATENT OFFICE.

THOMAS J. STEPHENS, OF CLEVELAND, OHIO.

SHAVING KIT.

Application filed January 30, 1922. Serial No. 532,646.

To all whom it may concern:

Be it known that I, THOMAS J. STEPHENS, a citizen of the United States, residing at Cleveland, in the county of Cuyahoga and State of Ohio, have invented certain new and useful Improvements in Shaving Kits, of which the following is a specification.

This invention relates to a shaving kit, and has for its object to provide a durable, compact, and easily manufactured group of pockets for shaving utensils, arranged in a casing in a manner to provide storage space for lather-forming material, such as a fluid or liquid; also to increase the capacity for storing such material by making the handle of the shaving brush into storage space, so conforming to the pocket that receives it as to reduce to a minimum loss of fluid storage space incident to development of the brush pocket; also to utilize the shape of the brush pocket to facilitate the introduction of the bristles thereinto; and, finally to so relate the pockets to the casing of the kit that in addition to dipping into the storage space of the casing from the end or ends thereof, they will be presented in such relation to a cover or covers applied to the casing as to adapt a cover to confine the article introduced into a pocket.

In order that the invention may be fully understood, the preferred embodiment thereof is shown in the accompanying drawing, in which—

Figure 1 is a central longitudinal section of a kit embodying in its construction the several features of the invention.

Figure 2 is an end elevation of parts shown at the upper end of Figure 1 with the cover removed.

Figure 3 is a vertical longitudinal section of parts shown in Figure 2 and at the upper end of Figure 1, the plane of section being at right angles to that of Figure 1.

1 represents a casing which may be of any desired transverse section, but here shown cylindrical, and serving as a container for a lather-producing substance for shaving. Inserted through one end of the casing 1 and centrally and longitudinally disposed therein is a brush pocket 2 composed of a tapered base 2^a which substantially fits the transverse dimension of the casing at the lower end thereof, and a prolongation 2^b which, together with the reduced portion of the base leaves an annular storage space 3

for lather-producing fluid. Base 2^a extends beyond the lower end of the casing 1 in order to present a flange 4 to receive the cover 5. Within the pocket 2 is a brush, the handle of which is constructed in the form of a dispensing container 6 corresponding substantially to the base of the pocket, so that the transverse dimensions of the container 6 and the portion of the reservoir 3 surrounding it approximate those of the casing 1, and loss of storage space incident to introduction of the pocket is at this portion of the casing reduced to a minimum; said brush further comprising a head 7 mounted upon the container 6 and carrying the bristles 8 which enter the barrel portion 2^b of the pocket. As herein shown, the container 6 is equipped with a valve 9 and a valve actuating rod 10 under control of the flexible bottom 11 of the container in order to adapt the container to supply lather-generating fluid to the bristles as described and claimed in my co-pending application Ser. No. 532,645, filed January 30, 1922.

Carried by the opposite end 12 of the casing 1, and intruded therefrom into the storage space 3, are a series of pockets 13, 14, and 15 for containing the blades, the handle, and the body of a razor; and these pockets are also arranged to occupy the least practicable space within the reservoir; that is to say, they are surrounded by storage space for the lather fluid. Pockets 13, 14, and 15, like the pocket 2 extend beyond the end of the casing 1 and are closed by a cover 16 which is adapted to confine the articles inserted in the pockets. End 12 is further provided with a delivery nipple 17 closed by a cap 18.

The bristle carrying head 7 is threaded to the handle 6 so as to render it readily removable, and when the container provided by the handle is opened by such removal, lather-producing fluid may be supplied to the container 6 from the reservoir 3.

The kit herein described is designed primarily for construction of readily molded plastic such as celluloid or other similar material, but obviously it may be constructed of sheet metal or any other suitable material.

I claim:

1. In a lather kit, a casing, a tapered brush pocket centrally and longitudinally disposed in said casing and forming therewith a sur-

2
rounding storage space, and a dispensing container located within and conforming to the taper of said pocket and thereby raising the storage capacity of one portion of the 5 kit to approximately the entire transverse section of said portion.

2. In a shaving kit, a casing, a brush pocket centrally and longitudinally disposed in said casing and having a tapered portion 10 and an elongated portion beyond the tapered portion, said pocket forming with said casing annular storage space for lather-forming material, a brush inserted in said pocket comprising a dispensing container 15 conforming substantially to the tapered portion of the pocket and thereby raising the storage capacity of that portion of the kit, and bristles carried by said dispensing container, guided by said tapering portion into 20 the prolongation of said pocket.

3. In a shaving kit, a casing, a brush pocket extending centrally and longitudinally inward from one end of said casing and forming with the casing a surrounding 25 reservoir for lather-forming material, and pockets carried by the opposite end of said

casing and dipping into said annular reservoir.

4. In a shaving kit, a casing, a brush pocket centrally and longitudinally disposed in said casing and substantially corresponding to the casing in longitudinal dimension and also in transverse dimension at one end but tapered longitudinally to develop a surrounding reservoir and facilitate the 35 insertion of the bristles of the brush into the reduced end of the pocket.

5. In a shaving kit, an outer casing wall, a pocket forming wall within and secured at one end to an end of the casing wall; said 40 walls forming a reservoir for lather-producing material, and a cover for said casing; said pocket forming wall extending outwardly beyond the end of the casing wall; and said cover being adapted to receive the 45 outwardly extending portion of the pocket wall and to confine an article inserted in the pocket.

Signed at Cleveland, Ohio, this 23rd day of January, 1922.

THOMAS J. STEPHENS.
